UNITED STATES PATENT OFFICE.

SIMON EISENSTEIN, OF BERLIN, GERMANY.

WIRELESS SIGNALING SYSTEM.

No. 851,621.

Specification of Letters Patent.

Patented April 23, 1907.

Original application filed August 25, 1905, Serial No. 275,795. Divided and this application filed July 8, 1906. Serial No. 324,667.

To all whom it may concern:

Be it known that I, SIMON EISENSTEIN, a subject of the Emperor of Russia, and residing at Berlin, in the Empire of Germany, 5 have invented a new and Improved Wireless Signaling System to be used in Connection with a Multiphase Alternating Current, of which the following is a specification.

My invention relates in general to senders 10 of wireless signaling systems, whereby a very sharp selectivity is attained and any listening with a telephone is rendered most difficult; and in particular, my invention relates to the kind of wireless signaling systems in 15 which the spark gap is contained not in a secondary circuit, or in secondary circuits, of the aerial conductor, but is contained in the aerial conductor itself.

My invention consists in operating a wireless 20 signaling system of this kind with, or by means of a multiphase alternating current, the aerial conductor being divided in this case into as many branches as there are phases in the multiphase alternating current, 25 and each of said branches containing a spark gap, as more fully described hereinafter.

In order to make my invention more clear, I refer to the accompanying drawings in 30 which similar letters denote similar parts throughout the several views and in which:

Figure 1 is a diagram which will be referred to later on, Fig. 2 is another diagram which also will be referred to hereinafter, and Fig. 3 is the diagram of the sender shown as an example.

Concerning the substitution of a single phase alternating current by a multiphase alternating current in general, and the advantages to be derived therefrom in particular, I refer to my application Serial Number 40 275,795 filed August 25th 1905, of which this is a divisional application and which also refers to a wireless signaling system the gist of which is just the substitution of the one kind of current by the other. But, while, in said 45 other application the multiphase alternating current is used in connection with a sender in which secondary circuits are associated with the sending circuit, the spark gaps being situated in said secondary circuits, I now divide the aerial conductor in as many branches as there are phases in the multiphase alternating current, each of said branches being provided with a spark gap, the number of these 55 gaps being thus also equal to that of the phases.

Referring to Figs. 1 and 2, these are exact copies of Figs. 1 and 2 of the before mentioned specification, Serial Number 275,795. I have preferred to show these figures also in the 60 present specification to do away with the necessity of studying also the other one in so far as these two figures are concerned. And from the same reason I cite here some paragraphs from the other specification, as follows:

In the hitherto known wireless signaling systems it was customary to employ a single phase alternating current for energizing the sending circuit, which is controlled by a 70 Morse key. The single phase alternating current, however, presents the disadvantage, that it is not possible to thereby attain so high a number of discharges as to avoid any listening with a telephone with perfect 75 safety. For practical reasons the current is required to have from 50 to 100 periods at the most, as otherwise the capacity would be too insignificant. Even with a single phase alternating current with 100 periods the 80 number of discharges is so small that it is easy to listen to the messages with a telephone, as is well known. In general the discharges take place in the proximity of the maximum of the tension of the current, 85 which is marked by the perpendicular A in Fig. 1, where the curve of the single phase alternating current is shown. It would be useless to increase the discharge complex (indicated by the hatched surface a or a') by so 90 adjusting the spark gap, that the discharges take place already at a lower tension, as thereby the disadvantage mentioned above is not avoided. For removing the said disadvantage, the single phase alternating current is according to my invention replaced by a multiphase alternating current. Fig. 2 shows for example the curve of a triphase alternating current, from which it will be apparent, that it is now possible to obtain more 95 discharge complexes than hitherto, the discharges taking place in the proximity of the perpendiculars A, B, C, A', B', C', which represent the maxima of the tension. Evidently by the adoption of an alternating current 100 with a high number of phases, say a six phase or a nine phase alternating current, it is possible to so increase the number of discharges as to render a listening with the telephone impossible. In all cases the frequency 105 can be kept within practically allowable limits, say between 50 and 100 periods. When

assuming a triphase alternating current and it is desired to avoid any listening with a telephone, of course it will be necessary to so adjust the spark gap, that the discharges take place already at a lower tension, as is indicated by the hatched surface a, b, c, a', b', c' , which represent the discharge complexes. As each complex comprises a whole series of consecutive discharges, of course the number of discharges is thereby increased in the desired degree.

As to the sender itself, this may be constructed in most various manners without departing from the spirit of the invention. In the form of construction shown as an example in Fig. 3, it is supposed that the system is to operate with, or by means of, a triphase alternating current. Therefore, the aerial conductor is divided into 3 branches 1, 1, 1 corresponding to the three phases of the alternating current employed. Each conductor branch 1 contains a spark gap 6, while beneath the three spark gaps 6, 6, the three branch conductors 1, 1 are connected by their main with an earth-plate E, as usual.

The three spark gaps 6, 6 are severally connected with the secondary coils of three transformers 8, 9 and 10, the primary coils of which are connected on the one hand with a common point 11 in the sending circuit and on the other hand with the three collector rings respectively of the alternator.

Having now described my invention what I desire to secure by a patent of the United States is:

In a wireless signaling system, the combination with a sending circuit, of means for supplying a multiphase alternating current to said sending circuit, an aerial conductor, divided into as many branches as there are phases in the multiphase alternating current, and a spark gap in each of said branches.

In testimony, that I claim the foregoing as my invention, I have signed my name in presence of two subscribing witnesses.

SIMON EISENSTEIN.
